PATENTED SEPT. 5, 1905.

C. E. DE LONG.
WATCH WINDING INDICATOR.
APPLICATION FILED JUNE 15, 1904.

UNITED STATES PATENT OFFICE.

CHARLES E. DE LONG, OF SOUTH McALESTER, INDIAN TERRITORY,
ASSIGNOR TO FRED McINTYRE, OF SOUTH McALESTER, INDIAN
TERRITORY.

WATCH-WINDING INDICATOR.

No. 798,884.

Specification of Letters Patent.

Patented Sept. 5, 1905.

Application filed June 15, 1904. Serial No. 212,724.

To all whom it may concern:

Be it known that I, CHARLES E. DE LONG, a citizen of the United States, residing at South McAlester, Indian Territory, have invented a certain new and useful Improvement in Winding-Indicators for Watches, of which the following is a full, clear, and exact description, such as will enable others skilled in the art to which it appertains to make and use the same, reference being had to the accompanying drawings, forming part of this specification, in which—

Figure 1 is a top plan view of the indicator-train and the ratchet of a time-train which coöperates therewith. Fig. 2 is a vertical longitudinal sectional view through the ratchet and the arm carrying the gear for imparting reverse motion to the indicator-train. Fig. 3 is a top plan view of a portion of the indicator-train, part of the ratchet being broken away to indicate the manner in which the actuating-arm is attached thereto. Fig. 4 is a fragmentary view of one of the intermediate gears and the hollow arbor surrounding the seconds-hand arbor. Fig. 5 is a vertical longitudinal sectional view through the mechanism about the seconds-hand arbor. Fig. 6 is a vertical longitudinal sectional view through the indicator-train, the arbors being illustrated in elevation; and Fig. 7 is a view in elevation of a watch constructed in accordance with my invention.

This invention relates to an improvement in timepieces; and it is particularly applicable to use in connection with watches.

One of the objects of the invention is to provide an attachment which will constantly indicate the extent to which the mainspring of the timepiece is wound, so that an observer may know not only when the spring is fully wound or when it is run down, but also the extent to which it is wound at any particular moment, the number of hours which have elapsed since rewinding, and when it will require rewinding.

It is the particular purpose of this invention to adapt the improvement to watches as they are now generally constructed.

It is also the purpose of this invention to provide an indicating means which may be operated by a very slight expenditure of power on the part of the usual train or movement to adapt it for application without changing the movement in other respects and to

avoid interference thereby with the usual action of the other parts. To this end I provide the indicator element, which is actuated by suitable means coöperating with the winding device, so that the act of winding the mainspring causes the indicator element to be actuated in such a manner that it indicates the extent to which the winding is carried. I preferably arrange the indicator element to coöperate with a graduated scale, so that the winding of the mainspring will cause the indicator element to move over or pass a graduated scale. As the mainspring runs down the indicator element will receive motion through suitable intermediate gearing from the barrel, so that it will gradually be moved backward over the scale toward its original position, indicating the progress of the unwinding action. As certain gearing necessary to transmit motion from the ratchet to the indicator-train is unnecessary for transmitting the reverse motion from the barrel to the indicator, provision is made for throwing such needless gearing automatically out of action as soon as the act of winding ceases or to such a point as would indicate that the watch has been rewound. In fact, provision is made for automatically releasing the motion-transmitting gearing from the ratchet as soon as the winding ceases. This automatic disconnection is best secured by permitting a slight retrograde of the ratchet at the end of the winding action through the medium of the principle of a yielding pawl, which has been in use for many years on fine watches to prevent straining the mainspring, the retrograde motion having the effect of automatically carrying the actuating-gear out of engagement with the gear or gears of the indicator-train.

Referring now to the drawings by numerals of reference, the numeral 1 designates the usual barrel, and 2 designates the arbor therefor. Carried by the arbor and illustrated as being secured on the head 3 thereof is a ratchet 4, having an undercut hub 5, surrounding which is a yielding split collar 6, terminally secured or formed on one end of a swinging arm 7. The collar is so constructed that under normal conditions its binding tendency will be sufficient to cause it to frictionally engage the undercut hub, so that a movement of the ratchet will impart a movement to the arm. Any resistance to the arm, however, sufficient to arrest its movement will

permit the ratchet to rotate irrespective thereof, as will be explained hereinafter.

Carried by the arm 7 is a compound gear-wheel 8, having two sets of teeth, (designated as 9 and 10, respectively.) The smaller number of teeth act as pinion-teeth and mesh with the peripheral teeth on the ratchet. These teeth 9 are at all times in engagement with those on the ratchet, while the larger number 10 of teeth (designated as 10) are only periodically in engagement with the teeth on one of the wheels of the indicator-train. The compound gear 11 is fixed on an arbor 12 and rotates therewith. This arbor has a bearing at 13 in the top plate of the timepiece and a bearing 14 in the bottom plate. Interposed between the top and bottom plates of the timepiece and frictionally sleeved upon the arbor 12 is a slip-pinion 15. This pinion is provided with depending yielding walls the ends of which are capable of engaging the grooved portion 16 of the arbor 12, so that under normal conditions said pinion will move with the arbor; but under abnormal conditions the arbor is capable 25 of moving independently of any movement of the pinion. This slip-pinion is in mesh with the teeth of the barrel-gear and is so disposed that the rotation of the barrel will impart movement to the pinion, causing the arbor to 30 rotate, carrying with it the compound gear 11. The gear 11 is provided with two sets of teeth, (designated by the numerals 17 and 18, respectively.) Those designated by the reference-numeral 17 are designed to mesh with 35 the teeth 19 on an intermediate gear 20, which is carried by an arbor 21 in the bottom plate of the watch. This arbor 21 has a reduced portion 22, on which is fixedly secured a pinion 23, while the gear 20 is only frictionally 40 held to said arbor. As indicated in Fig. 6, the gear 20 rests upon the flange 24 of the arbor 21, and interposed between the gear 20 and the pinion 23 is a tension plate or disk 25, the resiliency of which is sufficient to hold 45 the gear 20 in frictional engagement with the arbor 21 under normal conditions. However, when subjected to undue strain the gear 20 may rotate irrespective of the arbor or its pinion. The indicator-wheel 26 is in mesh 50 with the pinion 23 and is provided with a hub 27, revolvably mounted upon a hollow arbor 28, carried by a plate 29, fixed to the bottom plate of the timepiece. This hollow arbor 28 is concentric with and surrounds the seconds-hand arbor, (designated by the reference-numeral 30,) on which the seconds-hand 31 is secured. The hub 27 of the indicator-wheel 26 is beneath the seconds-hand and carries an indicating element, illustrated as a 55 pointer 32, which is disposed in a depression or recess 33 in the dial 34. Above the depression is a graduated scale indicating the seconds, while in the floor thereof the graduated scale is arranged to coöperate with the 60 indicating-hand, so as to designate the wind-

ing condition of the mainspring or, in other words, to clearly show the number of hours elapsing since the timepiece had been wound and the number of hours which it yet had to run. By providing the indicating element in 70 axial alinement with the arbor of the seconds-hand the indicator can be readily observed and the indicating-wheel may be conveniently positioned within the watchcase without interfering with the remainder of the works. 75

In Fig. 3 I have illustrated two positions of the swinging arm 7. The normal position is shown in full lines, while the dotted lines indicate the abnormal position, or the position which the arm assumes temporarily while the 80 indicator is being returned or, in other words, while the watch is being wound. As heretofore stated, the arm is frictionally secured to the hub of the ratchet, so that the initial movement of the ratchet in winding the watch 85 will carry the arm toward the indicator-train until the arm assumes the position indicated in dotted lines. The terminal projection 35 on the arm is designed to abut against the shoulder 36 in the plate when the initial winding 90 movement of the ratchet takes place, so that the teeth of the meshing gears will be permitted to come into operative engagement, but their intermeshing contact will only be such as to permit one to rotate the other, the teeth of 95 the respective gears being spaced by this projection so that they will loosely engage, and any tendency to bind will be avoided. When the operator begins to wind the timepiece, the arm and the compound gear carried thereby 100 will be caused to assume the position indicated in dotted lines in Fig. 3, and inasmuch as the smaller set of teeth on the gear 8 is continuously in mesh with the teeth of the ratchet the initial rotative movement of the ratchet 105 will impart a rotative movement to the gear 8, and as soon as the arm has moved over to the position indicated in dotted lines the teeth 10 on the gear 8 will mesh with the teeth 18 on the gear 11 to cause its rotation. The teeth 110 18 on the gear 11 being constantly in mesh with the teeth 19 on the gear 20, a rotary movement to this gear will be imparted, the friction of the tension device being such that a rotary movement will be imparted to the 115 arbor 21 and to the pinion 22, carried thereby. As a result the teeth on the pinion 23 being in mesh with the teeth on the indicator-wheel a retrograde movement will be imparted to the indicator-wheel, so that the indicator will be moved toward zero or toward the starting-point. As soon as the operator ceases to wind the timepiece it is necessary 120 that the operating-gear 8 be thrown out of engagement with the indicator-train. This is permitted and accomplished by means of the spring-pressed pawl 37, which is provided with an elongated slot 38, through which the pin 39 projects. The elongated slot in the pawl permits the retrograde movement of 125 130

the ratchet for at least a distance equal to the length of the slot, so that at each relaxation of the winding of the mainspring the gear 8 is automatically thrown out of engagement 5 with the indicator-train. After the timepiece has been wound and the indicator moved to the starting-point a movement will be imparted to the indicator-wheel to move the indicator a distance commensurate with the amount 10 of travel of the barrel due to the running down of the mainspring. This movement will be imparted through the medium of the gear on the barrel, which meshes with the slip-pinion 15 70 on the arbor 12. The teeth 10 on the gear 8 are in excess of the teeth 18 on the gear 11. The reason for this is to insure the return of the indicator-hand to zero when the mainspring is wound. Otherwise the engagement and disengagement of the actuating-wheel with the complementary gear of 20 the train might not cause the hand to be returned to zero. As the arbor is rotated the gear 11 will have a movement imparted thereto in a direction reverse to that imparted during 25 the winding movement, which movement will be communicated to the indicator-wheel through the medium of the train heretofore described. The gear 26 is constructed with a sufficient number of teeth to cause the indicator to travel to zero, or its starting-point, 30 but not move beyond the same. The passing of the indicator beyond the starting-point is prevented by leaving a portion of the wheel toothless, as indicated at 40. For example, 35 suppose the indicator has reached the zero-point and the mainspring has not yet been completely wound. The toothless portion 40 in the wheel will cause the pinion 23 to remain stationary, while the rest of the indicator-train will be permitted to rotate with the ratchet, as explained below, until the complete winding has been effected. As soon as 40 the winding has been completed and the actuating gear-wheel 8 has been released from the 45 train the forward movement of the indicator-wheel will commence.

The only radical departure from the ordinary watch is that the ratchet is somewhat larger in proportion to the time-train than 50 the ratchet usually employed. In order that the ratchet may readily be applied to and detached from the rectangular portion of its arbor, the crown-wheel 41 of the winding-train is lowered in the plate so that its periphery 55 will pass beneath the ratchet and so that each element may readily operate without interfering with the other. Of course it is to be understood that I prefer to utilize an indicator pointer or hand in connection with this indicator-wheel; but I also reserve the right to 60 place suitable characters on the wheel, and by providing an opening in the dial, so that these characters will be exposed to view, I may dispense with the hand. I also reserve the right 65 to make such other changes or alterations in

this invention such as relate to form, proportion, and minor details of construction and without departing from the spirit of the invention or sacrificing any of the advantages thereof. Attention is also directed to the 70 fact that I prefer to employ fine teeth on the gears 8 and 11. These teeth besides being fine are pointed, this being a distinct departure from the coarse spur-gears used in previous constructions of watches, and the advantage of so arranging these teeth is that the teeth on the opposing gears will automatically engage and disengage in a more efficient manner than would gears having broad flat teeth. 75

Having thus described my invention, what 80 I claim, and desire to secure by Letters Patent, is—

1. In a winding-indicator for watches, the combination with a barrel-arbor, a ratchet-wheel 4 arranged thereon of a swinging arm 85 frictionally mounted on said barrel-arbor, a compound gear mounted on said arm, and in constant mesh with said ratchet-wheel 4, a winding-indicator train including a slip-pinion which is in constant mesh with the time-train, whereby the down movement is communicated from the time-train to the winding-indicator train, and means whereby when the watch is wound the compound gear engages the winding-indicator train and moves 90 the same on its up movement, the slip-pinion in said winding-indicator train permitting such reverse drive; substantially as described. 95

2. In a winding-indicator for watches, the combination with a spring-barrel, of a ratchet-wheel 4 in the form of a gear, an arbor for said spring-barrel and upon which said ratchet-wheel is arranged, an arm mounted on said arbor and carrying a compound gear at its end, one portion of which is in constant mesh 100 with the ratchet-wheel 4, and the other portion of which is provided with fine teeth, a time-train driven by the spring-barrel, a winding-indicator train normally driven by the time-train for driving an indicator-hand operating over the face of a winding-indicator dial, a compound gear in the winding-indicator train, one portion of which is in constant mesh with said train and the other portion of which is provided with fine teeth adapted to 105 mesh with the fine-toothed portion of the first-mentioned compound gear, a slip-pinion in the winding-indicator train, and means whereby when the watch is wound the fine-toothed portions of said compound gears are thrown 110 into mesh so that the indicator mechanism is actuated in a direction opposite to that in which it is driven when receiving motion from the time-train; substantially as described. 115

3. In a winding-indicator for watches, the combination with a spring-barrel and its ratchet in the form of a gear, an arbor for said spring-barrel, an arm carrying a compound gear at its end, one portion of which is 120

in constant mesh with the ratchet-gear of the spring-barrel and the other portion of which is provided with fine teeth, a time-train driven by the spring-barrel, a winding-indicator train 5 normally driven by the time-train for driving an indicator-hand operating over the face of a winding-indicator dial, means for arresting the winding-indicator hand at zero position, said means permitting the winding-indicator train to receive further motion, in the 10 act of winding the watch, without disturbing the position of said indicator-hand, a compound gear in the winding-indicator train, one portion of which is in constant mesh with 15 said train and the other portion of which is provided with fine teeth adapted to mesh with the fine-toothed portion of the first-mentioned compound gear, a slip-pinion in the winding-indicator train, and means whereby when the 20 watch is wound the fine-toothed portions of said compound gears are thrown into mesh so that the indicator mechanism is actuated in a direction opposite to that in which it is driven when receiving motion from the time-train; 25 substantially as described.

4. A winding-indicator for watches having a slip-pinion frictionally engaging its arbor and in mesh with the barrel-teeth of the watch, whereby the pinion may rotate independently of the arbor, and an intermediate pinion for 30 the train fixed on the arbor, said arbor frictionally engaging the slip-pinion; substantially as described.

5. A winding-indicator for watches including a slip-pinion in engagement with the teeth 35 of the barrel of the watch, an arbor on which the slip-pinion is frictionally mounted, a pinion on one end of the arbor, a second arbor, a pinion on the second arbor in direct mesh with the indicator-wheel, and a wheel in frictional engagement with the pinion and in constant engagement with the remainder of the indicator-train; substantially as described. 40

In testimony whereof I hereunto affix my signature, in the presence of two witnesses, 45 this 20th day of May, 1904.

CHARLES E. DE LONG.
